UNITED STATES PATENT OFFICE.

SAMUEL E. DITTMAN, OF CHICAGO, ILLINOIS, ASSIGNOR TO LETTERPRESS METHODS CORPORATION, OF CHICAGO, ILLINOIS, A CORPORATION OF ILLINOIS.

MANUFACTURE AND TREATMENT OF PRINTING PLATES.

Application filed December 21, 1922. Serial No. 608,373.

My invention relates to the manufacture of printing plates and the treatment thereof prior to the mounting of the plates in the printing press with a view toward reducing or eliminating the make-ready on the printing press, and has particular relation to the leveling of the plates although not limited to this use alone.

One feature of the invention resides in a simple and effective process for treating printing plates which does not require a great amount of time or skill in the practice thereof.

In describing the invention in detail reference is had to the accompanying drawings, forming a part of this specification, and wherein like characters of reference are used to designate corresponding parts throughout the several views, and in which—

Figure 1 is a partially sectional side elevation of a machine for treating plates by my process.

Figure 2 is a sectional view of the same taken at right angles to Fig. 1.

Figure 3 is an enlarged partial face view of a printing plate.

Figure 4 is an exaggerated partial section of the same on the line 4—4 of Fig. 3, with a treating sheet applied on the back thereof.

Figure 5 is a similar section of the plate, with the treating sheet applied on the back thereof, after the plate has been treated.

Figure 6 is an enlarged partial face view of a treating sheet.

Figures 7 and 8 are partial sections of the treating sheet taken respectively on lines 7—7 and 8—8 of Fig. 6.

A suitable press for the practice of my invention is illustrated in Figs. 1 and 2 and includes a frame 1 including a base 2, which constitutes a lower pressure member arranged to coact with an upper pressure member 3, slidably mounted in the frame, and actuated for vertical movement by a screw 4, threaded in a yoke of the frame and provided with an operating hand wheel 5. At its lower end the screw is formed with an ordinary swivel 6, arranged to turn within a cap 7, fixed to the upper pressure member. The machine is constructed of metal throughout, the opposing faces 8 of the pressure members being flat and unyielding, and bearers 9 are formed at two opposite ends of the upper pressure member and depend below the surface 8 of the upper pressure mem-

ber to engage the surface 8 of the lower pressure member 2 to space the surfaces 8 under pressure. In the preferred practice of my invention heat is employed as hereinafter described, and accordingly the pressure members 2 and 3 are provided with heating chambers 11, in which are disposed gas burners 12 which are connected with gas pipes 13 and 14, leading from a convenient source of gas supply, the pipe 13 being flexible to accommodate the vertical movement of the pressure member 3.

The treatment sheet of my invention, generally indicated at 15, includes a flat sheet of paper or other suitable material 16 to which is secured a pattern of material 17 of uniform thickness, normally hard and unyielding but adapted to be rendered plastic for displacement, the pattern providing uniform displacement throughout the material, and a second sheet of paper, or other suitable material, 18 conformed with the pattern of the material and secured to the opposite face thereof. See Figs. 6, 7, and 8. The two sheets of paper constitute support or backing sheets for the pattern of material and protect it, and where as shown the two sheets conform with opposite faces of the pattern of material a strong structure is provided which is well adapted to withstand shipment and storage.

The treatment sheet of my invention which is to be rendered plastic by the application of heat thereto includes a pattern of material 17 containing a solid substance in pulverized form and a binder adapted to be softened by the application of heat thereto to render the material plastic and preferably adapted to become hardened when cooled. A material of this character which functions very well contains equal parts of magnesia in pulverized form, wheat flour, and powdered graphite, and a suitable quantity of japan.

In treating a plate 19 it is facewise compressed between the surfaces 8 with a treatment sheet 15, containing the pattern of the material 17, interposed between the back of the plate and the respective surface 8 and with the pattern of material in plastic condition, by forcing the upper pressure member 3 downwardly by means of the screw 4 turned by the hand wheel 5. Under the pressure the material 17 displaces to conform the face of the plate with the respective surface 8, the material 17 displacing in

2

a varied manner, in correspondence with any varying thickness of the plate where the compression is effected between corresponding unyielding or flat unyielding surfaces, to exert sufficient pressure throughout the area of the plate to conform the face thereof with the respective surface 8, the pattern providing displacement space throughout the area of the material to avoid concentrating the pressure on any portion of the plate whereby the face of such portion of the plate might be injured by undue pressure thereon. Figs. 3 and 4 show the plate before treatment with a portion 21 of the face of the plate depressed and a portion 22 of the face of the plate projecting, the portion 22 overlying an unduly thick portion of the plate as shown in Fig. 4. Fig. 5 shows this portion of the plate after treatment with the depression and projection removed, and the pattern of material 17 of the treatment sheet displaced whereby the face of the plate was conformed with the respective surface 8 without concentrating pressure on the unduly thick portion of the plate underlying the portion 22 of the face thereof.

It is preferable to apply heat to the plate to render the plate more pliable during the compression and where heat is so used it is desirable to use a pattern of material 17 which is normally hard and unyielding and adapted to be rendered plastic under the heat whereby the heat is utilized for both purposes, the use of heat to soften the pattern of material having an advantage in that the material can be rendered uniformly plastic without particular skill or care being required.

The preferred manner of applying the heat to the plate and material is by heating the surfaces 8 which in the machine shown is effected by the gas burners 12. The degree of heat used for the above purposes is approximately 350° F. though it may be varied throughout a fairly large range.

Where heat is used to render the plate more pliable it is preferable to cool the plate, after it is treated to conform the face thereof, while held under compression in its conformed state whereby to prevent warping the same. This is effected by cooling the plate and the treatment sheet while they are unyieldingly held, with the treatment sheet applied on the back of the plate and in registered position with respect to the face of the plate, in their respective conformed and displaced states, for example, by permitting the surfaces 8 to cool with the plate and treatment sheet still under compression therebetween or by placing the plate and treatment sheet under compression in another press having flat unyielding compression surfaces which are cool.

After the plate is treated the back of the same is either shaved to level the same or

the treatment sheet, if it is adapted to be or become hardened, is left, in its displaced form and in hardened condition and in registry with the face of the plate, on the back of the plate, and preferably secured thereto, to form an even solid back or seat for the plate.

In the manufacture of duplicate plates from original plates or foundry forms the face of an original plate or foundry form is first corrected, as by treating the same to conform the face thereof to a desired surface, and then a duplicate plate is produced from the corrected face of the original whereby the duplicate is practically free from defects originally obtaining in the original, so that the correction of the duplicate, if any, is only to correct remainders of defects practically eliminated in the treatment of the original and such defects as obtained in the duplicate in the making of the same from the corrected face of the original. The duplicate plate so formed is thereafter preferably treated to conform the face thereof with the aforementioned desired surface.

The original plate or foundry form is preferably treated in the same manner hereinbefore described by facewise compressing the same between unyielding surfaces with a pattern of material in plastic condition, capable of being or becoming hardened, interposed between the back of the plate and the respective unyielding surface to conform the face of this plate with the respective unyielding surface. Then a mold of the conformed face of this original plate is formed, by pressing the same into a molding material, as is usual, but with the pattern of material in its displaced form and in hardened condition applied to the back of this plate and in registered position with the face thereof and with an unyielding surface supporting the pattern of material for maintaining the conformed face of this plate during the molding. Thereafter a duplicate plate is produced from the original, as by the usual electrotype method. Thereafter the duplicate plate may be again treated, if necessary, in the same manner as hereinbefore described. The original and duplicate plates may be treated in the machine illustrated in Fig. 1 as is obvious, and the back of the duplicate plate may be shaved after the treatment thereof to level the same in the usual manner.

This method of manufacturing duplicate plates from original plates or foundry forms produces a duplicate plate of a high degree of perfection without the usual tedious hand finishing of the duplicates which requires considerable skill and care.

In the use of the term printing plate I mean any printing plate such as an electrotype, type and cut form, composed type form, etc., as the method is applicable to all

kinds of plates or forms. Further in the use of the term original plate or foundry form I mean any plate or form used as an original from which duplicate plates are made.

While I have herein described and shown one embodiment of my invention I do not wish to be limited to the precise details thereof as changes may readily be made 10 without departing from the spirit of my invention but having thus described my invention I claim as new and desire to secure by Letters Patent the following:

1. The process of treating a printing plate consisting in facewise compressing the plate between unyielding surfaces with a pattern of suitable material in plastic condition interposed between the back of the plate and the respective unyielding surface, 15 said pattern affording displacement space throughout the area of said material and said material being adapted to displace under the pressure to conform the face of the plate with the respective unyielding surface.

2. The process of treating a printing plate consisting in facewise compressing the plate between corresponding, true, and unyielding surfaces with a pattern of suitable 30 material of uniform thickness and in plastic condition interposed between the back of the plate and the respective unyielding surface, said pattern providing uniform displacement space throughout the area of said material and said material being adapted to displace under the pressure to conform the face of the plate with the respective unyielding surface.

3. The process of treating a printing plate consisting in facewise compressing the plate between unyielding surfaces with a pattern of suitable material in plastic condition interposed between the back of the plate and the respective unyielding surface, 45 said pattern providing displacement space throughout the area of the material and said material being adapted to displace under the pressure to conform the face of the plate with the respective unyielding surface, and then shaving the back of the plate to level the same.

4. The process of treating a printing plate consisting in facewise compressing the plate between unyielding surfaces with a pattern of material, normally hard and unyielding and adapted to become plastic when heated, interposed between the back of the plate and the respective unyielding surface and applying heat to both the plate and the pattern of material to render the plate more pliable and to render the material plastic during the compression, said pattern providing displacement space throughout the area of the material and said material being adapted under the heat to dis-

place under the pressure to conform the face of the plate.

5. The process of treating a printing plate consisting in facewise compressing the plate between corresponding, true, and unyielding surfaces, heated to a point to render the plate more pliable, with a pattern of material of uniform thickness, normally hard and unyielding and adapted to become plastic under said heat, interposed between 70 the back of the plate and the respective unyielding surface, said pattern affording uniform displacement space throughout the area of the material and said material being adapted under the heat to displace under 80 the pressure to conform the face of the plate with the respective unyielding surface.

6. The process of treating a printing plate consisting in facewise compressing the 85 plate while heated to render it more pliable between unyielding surfaces with a pattern of material in plastic condition interposed between the back of the plate and the respective unyielding surface, said pattern 90 providing displacement space throughout the area of the material and said material being adapted to displace to conform the face of the plate with the respective surface, and then cooling the plate while held 95 under compression in its conformed state.

7. The process of treating a printing plate consisting in facewise compressing the plate between corresponding unyielding surfaces with pattern of material, normally hard and unyielding and adapted to become plastic when heated and to become hardened when cooled, interposed between the back of the plate and the respective unyielding surface 100 and applying heat to both the plate and the material to render the plate more pliable and to render the material plastic during the compression, said pattern providing displacement space throughout the area of the material and said material being adapted 110 under the heat to displace under the pressure to conform the face of the plate with the respective unyielding surface, and then cooling the plate and material while the plate and material are unyieldingly held, in the aforementioned relation and in registered position, under compression in their 115 respective conformed and displaced states.

8. The process of treating a printing plate consisting in facewise compressing the plate between flat unyielding surfaces, heated to a point to render the plate more pliable, with a pattern of material of uniform thickness, normally hard and unyielding and adapted to become plastic when heated and to become hardened when cooled, interposed between the back of the plate and the respective unyielding surface, said pattern 120 providing uniform displacement space throughout the area of the material and 125

said material being adapted under the heat to displace under the pressure to conform the face of the plate with the respective unyielding surface; and then cooling the plate and material by subjecting them in the aforementioned relation and in registered position to pressure between cool flat un-

yielding surfaces to hold them unyieldingly in their respective conformed and displaced states while cooling.

In witness whereof I hereunto affix my signature this eighteenth day of December, 1922.

SAMUEL E. DITTMAN.
